ATTORNEYS.

UNITED STATES PATENT OFFICE.

JOSEPH S. ISIDOR, OF NEWARK, NEW JERSEY, ASSIGNOR TO THE R. NEUMANN HARDWARE CO., A CORPORATION OF NEW JERSEY.

BAG-FRAME FASTENER.

Application filed June 9, 1921. Serial No. 476,162.

To all whom it may concern:

Be it known that I, JOSEPH S. ISIDOR, a citizen of the United States, residing at Newark, in the county of Essex and State of New Jersey, have invented certain new and useful Improvements in Bag-Frame Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in bag-frame fasteners; and, the present invention has reference, more particularly, to a novel construction of safety-latch or lock for bag-frames, which is especially adapted for use with the hinged frame-sections of that class of bag-frames, known as "English" frames, but which may be readily used with other styles of frames for the various kinds of travelling bags, suit-cases, and the like.

The present invention has for its principal object to provide a simply constructed and positively acting bag-frame fastener, provided with a hinged cover-plate from which the usual frame-section engaging post has been omitted, so as to prevent piercing of the frame-sections, the various devices and parts of the fastener being readily manipulated, to retain the hinged frame-sections in their closed relation, or for permitting the frame-sections to be brought into their separated or opened relation; and, furthermore to provide a bag-frame fastener in which the usual side-play between the hinged cover-plate and the box or casing of the fastener is positively overcome.

The present invention has for its further object to provide a novel construction of bag-frame fastener comprising a main box or casing adapted to be secured upon one of the frame-sections, and provided with a spring-controlled cover-plate hinged to said box or casing, and a stud-carrying plate hinged to the other frame-section, said hinged stud-carrying plate being adapted to be closed down over the main box or casing, and its stud being adapted to enter a hole or perforation in the top of the main box or casing, to secure the frame-sections

in their closed relation, and the spring-controlled cover-plate of the box or casing being adapted to be closed down over the closed stud-carrying plate, as will herein-after more fully appear.

Other objects of the present invention not at this time more particularly enumerated will be clearly understood from the following detailed description of the same.

With the various objects of the present invention in view, the said invention consists, primarily, in the novel bag-frame fastener hereinafter set forth; and, the said invention consists, furthermore, in the novel arrangements and combinations of the said parts, all of which will be more fully described in the following specification, and then finally embodied in the clauses of the claims, which are appended to and which form an essential part of the said specification.

The invention is clearly illustrated in the accompanying drawings, in which:

Figure 1 is a top or plan view of one of the angular portions of a bag-frame of the "English" type, showing in connection with the closed frame-sections, a bag-frame fastener made according to and embodying the principles of the present invention, the various parts of the fastener being represented in their closed or locked relation.

Figure 2 is an elevation of the various devices and parts shown in said Figure 1, looking in the direction of the arrow *x*; and Figure 3 is a similar view of the said devices and parts, looking in the direction of the arrow *y* in said Figure 1.

Figure 4 is a top or plan view of the same parts represented in said Figure 1, but showing the hinged cover-plate of the main box or casing in its open relation; and Figure 5 is a bottom view of the bag-frame fastener, detached from the bag-frame sections.

Figure 6 is a longitudinal vertical section of the bag-frame fastener, said section being taken on line 6—6 in said Figure 4; and Figure 7 is a transverse vertical sectional representation of the various devices and parts, said section being taken on line 7—7 in said Figure 1.

Similar characters of reference are employed in all of the said above described views, to indicate corresponding parts.

Referring now to the several figures of the drawings, the reference-character 1

indicates the main member of the outer frame-section, to which is secured by the usual and suitably disposed bracket 2, the usual vertical frame member 3, and 4 indicates the main member of the inner frame-section, to which is secured by the usual and suitably disposed brackets 5, the usual vertical frame-member 6.

While in the accompanying drawings I have shown, and in the following specification I have described my novel construction as applied to an "English" bag-frame, it will be clearly understood that the bag-frame fastener to be presently described, may be secured to and used with the hinged bag-frame sections of any other well-known constructions.

The bag-frame fastener, made according to the principles of the present invention, consists, essentially, of a suitably formed shell or casing comprising a top 7, longitudinally extending sides 8, and ends 9, the said ends being provided with downwardly extending fastening lugs or ears 10 which are passed through suitably disposed slits 11 in the main frame-section member 1 for securing the said shell or casing in its fixed position upon said frame-section.

As shown more particularly in Figures 4 and 6 of the drawings, the top 7 of the said shell or casing is made with a laterally extending depression, as 12, of suitable depth and width, and for the purposes to be presently more fully set forth, the depressed portion of the said top 7 being also provided with a suitably disposed hole or perforation 13. Adjacent to an opening 14 in said top 7, are suitably disposed and upwardly projecting pintle-receiving ears 15 in which is suitably secured a pintle 16, said pintle extending laterally across the said opening 14.

The reference-character 17 indicates a suitably formed cover-plate, provided with pintle-receiving ears, as 18, which extend down into the said opening 14, between the previously mentioned ears 15, for pivotally mounting said plate 17 upon the pintle 16, substantially as shown. To maintain the said plate 17 in its raised or closed positions, the said plate is made with a spring-engaging lug or tongue 19, as shown in Figure 6 of the drawings, said lug or tongue being in slidably engagement with the free end-portion of a spring-plate 20, disposed within the said shell or casing, and suitably secured against the inner face of the top 7 of said shell or casing by means of rivets 21, or other suitable fastening means. As shown, the said spring-plate is also provided with an elongated opening 22.

The reference-character 23 indicates a suitably formed stud-carrying latch-plate, adapted to extend laterally across the top 7 of the previously-mentioned shell or casing which is secured to the frame-section mem-

ber 1, said latch-plate when in its closed or locked relation with the said shell or casing fitting into the previously-mentioned depression 12, and being provided with a stud 24 which enters the hole or perforation 13 and also extends down into the opening 22 in the spring-plate 20, as will be clearly understood from an inspection of Figures 4, 5, 6 and 7 of the drawings. At one end, the said stud-carrying latch-plate 23 is suitably bent, as at 25, to provide a fingerpiece, and at its other end, the said plate 23 is bent to provide a pintle-receiving means, as 26, in which is disposed a pintle 27. Connected with the end-portions of said pintle 27 are a pair of links 28, said links being also connected with a second pintle 29, oscillatorily disposed in a pintle-receiving means or eye 31 of a bracket-member 30 which is secured by means of rivets 32, or otherwise, to the side of the vertical frame-section member 6, substantially as will be clearly understood from an inspection of Figures 3 and 7 of the drawings.

Having in the foregoing described in a general manner the construction of a bag-frame fastener embodying the principles of the present invention, any further description of the operation of the same is deemed unnecessary, such operation of the various devices and parts being readily understood from an inspection of the several figures of the drawings.

It must be noted, however, that the width of the stud-carrying latch-plate 23 is substantially that of the depression 12 in the top 7 of the shell or casing of the fastener, so that when the cover-plate 23 has been raised, and the latch-plate made to enter the depressed part 12, the latter plate will snugly fit said depressed part, and being in perfect registration, any side-play or movement of the parts are entirely overcome, and a perfect locking of the frame-sections will be the result.

I claim:

1. In combination with a pair of hinged bag-frame sections, a bag-frame fastener comprising a casing mounted upon one of said frame-sections, said casing being provided with a latch-plate receiving depression, a cover-plate connected with said casing and adapted to be moved over said depression, a bracket-member attached to the vertical face of the other frame-section, a latch-plate, a means of pivotal connection comprising links for flexibly connecting said latch-plate with said bracket-member, said latch-plate being adapted to be moved into registration with said depression, and means connected with said latch-plate adapted to be brought into locked engagement with the depressed portion of said casing.

2. In combination with a pair of hinged bag-frame sections, a bag-frame fastener comprising a casing mounted upon the up-

- per surface of one of said frame-sections, said casing being provided with a latch-plate receiving depression, a cover-plate connected with said casing and adapted to be moved over said depression, a latch-plate connected with the outer vertical face or side of the other frame-section, said latch-plate being adapted to be moved above and over said casing into registration with said depression, the depressed portion of said casing being provided with a perforation, and a stud extending from said latch-plate, said stud being adapted to enter said perforation for locked engagement with said casing.
5. In combination with a pair of hinged bag-frame sections, a bag-frame fastener comprising a casing mounted upon one of said frame-sections, said casing being provided with a laterally extending latch-plate receiving depression, a bracket-member attached to the vertical face of the other frame-section, a latch-plate, a means of pivotal connection comprising links for flexibly connecting said latch-plate with said bracket-member, said latch-plate being adapted to be moved into registration with said depression, and a cover-plate connected with said casing, said cover-plate being adapted to be moved over said receiving depression and over the latch-plate in said depression.
6. In combination with a pair of hinged bag-frame sections, a bag-frame fastener comprising a casing mounted upon the upper surface of one of said frame-sections, said casing being provided in its top with a laterally extending latch-plate receiving depression, a latch-plate pivotally connected with the outer vertical face or side of the other frame-section, said latch-plate being adapted to be moved above and over said casing into registration with said depression, a cover-plate pivotally connected with said casing, and a spring in said casing having a portion in engagement with said cover-plate for forcing said cover-plate over said receiving depression and over the latch-plate in said depression.
3. In combination with a pair of hinged bag-frame sections, a bag-frame fastener comprising a casing mounted upon one of said frame-sections, said casing being provided with a laterally extending latch-plate receiving depression, a spring-controlled cover-plate pivotally connected with said casing and adapted to be closed down over said depression, a bracket-member attached to the vertical face of the other frame-section, a latch-plate, a means of pivotal connection comprising links for flexibly connecting said latch-plate with said bracket-member, said latch-plate being adapted to be moved into registration with said depression when said cover-plate is raised, and means connected with said latch-plate adapted to be brought into locked engagement with the depressed portion of said casing.
- 20 30 35 40 45
4. In combination with a pair of hinged bag-frame sections, a bag-frame fastener comprising a casing mounted upon the upper surface of one of said frame-sections, said casing being provided with a laterally extending latch-plate receiving depression, a spring-controlled cover-plate pivotally connected with said casing and adapted to be closed down over said depression, a latch-plate pivotally connected with the outer vertical face or side of the other frame-section, said latch-plate being adapted to be moved above and over said casing into registration with said depression, a cover-plate pivotally connected with said casing, and a spring in said casing having a portion in engagement with said cover-plate for forcing said cover-plate over said receiving depression and over the latch-plate in said depression.
- 75 80 85
- In testimony, that I claim the invention set forth above I have hereunto set my hand this 7th day of June, 1921.
